BRACELESS PANIC RELEASE, ROLLER
LATCHING, REVOLVING DOOR HARD-
WARE

John W. Shields and Thurloe M. Hagenbook,
Evansville, Ind., assignors, by mesne assignments,
to International Door Company, Evansville, Ind., a corporation of Illinois

Application April 6, 1934, Serial No. 719,390

21 Claims. (Cl. 20—18)

Our invention relates broadly to revolving doors and more particularly to a construction of braceless panic release roller latching revolving door hardware.

One of the objects of our invention is to provide a simplified construction of panic release device for revolving doors capable of inexpensive manufacture on a quantity production basis.

Another object of our invention is to provide a construction of panic release hardware for revolving doors in which laterally extending braces are wholly eliminated.

Still another object of our invention is to provide a construction of pressure release hardware for revolving doors employing a latching roller member for maintaining the doors in normal position with means for adjusting the tension to which said latching roller members are subjected for controlling the pressure at which the revolving doors will collapse under panic conditions.

A further object of our invention is to provide a construction of braceless panic release roller latching revolving door hardware in which a minimum number of parts are employed for insuring a positive latch for the revolving doors in normal position while allowing collapsing of the doors to panic position and the maintenance of the doors in a prearranged position when the doors have been collapsed under conditions of panic.

Other and further objects of our invention reside in the construction of carrier for the roller latching members in revolving door hardware, as set forth more fully in the specification herein-after following by reference to the accompanying drawings, in which:

Fig. 1 is a front elevation of a revolving door provided with our improved braceless panic release hardware; Fig. 2 is a horizontal section taken on line 2—2 of Fig. 1; Fig. 3 is a fragmentary horizontal section on an enlarged scale showing one of the door wings in normal position and the remaining wings, due to unusual pressure being exerted against them, in the position they assume when collapsed; Fig. 4 is a top plan view of the housing with a portion thereof broken away and shown in section; Fig. 5 is a transverse section on line 5—5 of Fig. 4; Fig. 6 is a fragmentary sectional view taken on line 6—6 of Fig. 4; Fig. 7 is a plan view of the coacting central housing; Fig. 8 is a sectional view taken on line 8—8 of Fig. 7; Fig. 9 is a fragmentary horizontal section taken on line 9—9 of Fig. 10, showing the latching roller carried by the central member; Fig. 10 is a central vertical longitudinal

section through the central portion of our improved braceless panic release hardware; Fig. 11 is a horizontal section taken on line 11—11 of Fig. 10; Fig. 12 is a horizontal section taken on line 12—12 of Fig. 10; Fig. 13 is a similar view with one of the wings collapsed; Fig. 14 is a transverse vertical section taken on line 14—14 of Fig. 10; Fig. 15 is a transverse vertical section taken on line 15—15 of Fig. 10; Fig. 16 is a transverse vertical section taken on line 16—16 of Fig. 10; Fig. 17 is a detailed front elevation of the latching member carrying the eccentric adjusting pin; Fig. 18 is a side elevation thereof; Fig. 19 is a horizontal section taken on line 19—19 of Fig. 11; Fig. 20 is a front elevation of our improved revolving door hardware showing more particularly the enclosure plates and adjacent parts, one of the wings being broken away and in section; Fig. 21 is an end elevation of one of the housing plates; Fig. 22 is a front elevation thereof; Fig. 23 is a horizontal section taken on line 23—23 of Fig. 22; Fig. 24 is a horizontal section taken on line 24—24 of Fig. 22; Fig. 25 is a vertical transverse section on line 25—25 of Fig. 22; Fig. 26 is a vertical transverse section taken on line 26—26 of Fig. 22; Fig. 27 is a front elevation of the coacting enclosure plate; Fig. 28 is a transverse section taken on line 28—28 of Fig. 27; Figs. 29 and 30 are, respectively, a plan view and a side elevation of the abutment member with which the latching roller contacts; Fig. 31 is a plan view of the latching member carrying the roller; Fig. 32 is a central vertical longitudinal section taken on line 32—32 of Fig. 31; Fig. 33 is a top plan view of one of the pivoting members used in connection with our improved hardware; and Fig. 34 is a central vertical longitudinal section taken on line 34—34 of Fig. 33.

Referring to the drawings in more detail, the revolving doors have been indicated in Figs. 1 and 2 at 31, 32, 33, and 34 in normal position and mounted on a vertical axis by means of a sleeve member, indicated generally at 43 rotating in upper and lower bearings having its lower extremity 35 journaled in socket 36 and its upper extremity 37 journaled in socket 38. Socket 36 is mounted in the floor structure indicated at 39, while socket 38 is mounted in the upper structure indicated at 40. Socket 36 may be tapered to receive the end of the sleeve member 43. A 50 rod is provided interiorly of the sleeve member 43 and is provided with a projecting knob which projects out of the sleeve about thirty inches above the floor for allowing the door to be moved out of its position. The several doors are pro- 55

vided with suitable guard means indicated generally at 41. The hardware constituting the braceless panic release roller latching device is indicated in the upper and lower positions on the revolving door at 44 and 45.

In Figure 3, I have shown the braceless panic release roller latching revolving door hardware in which door 32 is in normal position, but wherein doors 31, 33, and 34 are in collapsed position due to the pressure exerted against them under conditions of panic. The sleeve 43 which supports the doors has a longitudinally extending groove 43a therein coacting with a groove 1a formed in the carrier 1 and groove 2a formed in housing 2, forming coacting key-ways for the key 44. The housing 2 is a casting shown more clearly in Figs. 4, 5, and 6 having a central sleeve portion shown at 46 having a cylindrical bore extending therethrough for receiving sleeve 43 and a substantially rectangular external periphery having pockets on each face thereof for receiving the ends of springs 21 which form the control means for the latching rollers for each of the wings of the revolving door. The pockets are formed from the flat side walls of the central rectangular portion 46 intermediate the outwardly protruding corners of the said central portion 46. The housing 2 is provided with a hollow interior and side walls which extend in four radial directions, as shown. Each of the hollow arms of the housing 2 is provided with an aperture 2b through which a tool is inserted for adjusting the tension of spring 21. Each of the hollow casings forming the arms of housing 2 is provided with a side opening represented at 2c into which eccentric 7 is fitted and locked into position by pins 18 for coaction with the roller carriers 9 as will be described hereinafter in more detail. The carrier 1 is connected with housing 2 by means of screws 24 which pass through apertures 1b and carrier 1 and into the countersunk screw-threaded recesses 2d in housing 2. Each of the radially disposed revolving doors is provided with hanger sections 15 and 16 constituting the upper support 44 and the lower support 45. The hanger sections 15 and 16 are secured on opposite sides of the door by means of bolts 17, as shown. The structure of the hanger is more clearly set forth in Figs. 20-28 from which it will be seen that plate 15 is provided with rearwardly projecting bosses 15a coacting with the inwardly projecting integral bosses 16a on hanger section 16.

The hanger sections are shaped to receive the carrier 1 and housing 2 and to form a pocket within the mortise cut in the door in which pocket, the carrier and housing are arranged to operate. The rearwardly projecting portion 15b on hanger section 15 is provided with a vertically disposed journal represented generally at 15c for receiving the pin member 6. Pin member 6 projects through the bore 3a in the swinging member 3. Swinging member 3 is more clearly represented in Figs. 33 and 34 as having a horizontally extending bore 3b disposed normal to the vertically extending bore 3a. The swinging member 3 has an arcuate shaped face 3c thereon coacting with the circular face of the carrier 1. Swinging member 3 has a vertically projecting stud 3d thereon which enters the aligned aperture 1d in carrier 1. There are four of the swinging members 3 each having an upwardly projecting stud 3d and each projecting into an aperture 1d in the carrier 1. There are four symmetrically disposed apertures 1d in the carrier 1 for receiving

the four studs 3d. The swinging members 3 are capable of limited annular movement from a position radial with respect to the center of sleeve 43 to a position limited by abutment of the swinging members 3 with the carrier 1, as shown more clearly in Figs. 12 and 13. The collapsed position of three of the swinging members 3 is shown more clearly in Fig. 3 wherein doors 31, 34, and 33 are collapsed, but wherein door 32 has not as yet moved to collapsed position. It will be observed that swinging members 3 are pivoted about pins 6 allowing the doors to swing out of aligned position with respect thereto, as shown at, for example, in the position of door 33 in Fig. 3. The pins 6 are each provided with recesses which we have represented at 6a, which recesses are adapted to receive a locking means by which the doors are maintained in a radial position. The swinging members 3 serve as a carrier for the elements of the locking means, which elements we have shown as ball 23 and a pressure communicating rod member 4. Ball 23 which is immediately adjacent the carrier 1 tends to seat in the recess 1e when the swinging member 3 is moved to the position in which the doors are collapsed which permits displacement of the pressure rod 4 and the retraction of the second ball 23 from recess 6a in pin 6 thereby allowing the door to be swung to collapsed position. The pin 6 is keyed to the hanger section 15 by means of a set screw 22 which passes through a threaded aperture in the rearwardly projecting portion 47. The rearwardly projecting portion 47 has a vertically extending bore therein which receives the pin 6, enabling the pin 6 to be anchored by means of set screw 22 with the upper portion thereof and project downwardly and through the recess 8a in the insert 8, as shown more clearly in Figs. 9 and 10. The hanger section 15 has the rearwardly projecting portion 47 thereof provided with a horizontally extending recess 15b of a diameter slightly larger than the projecting stud of the insert 8 so that pin 6 may retain the stud 8 in position whereby the engaging surface thereof shown at 8b may serve as a latch with respect to roller 14. The dimensions of the rearwardly projecting portion 47 of hanger section 15 and the contour thereof are such that the housing 2 and the carrier 1 are wholly embraced thereby. The bolt member 17, by which the hanger sections are secured on opposite sides of the door wings and united in a position to maintain the latching and locking means and swinging member in position, insures the continuous alignment of the several component members of the hardware.

The roller members 14 which are mounted in the radial arms of the housing 2 are each adjustable with respect to spring tension. The tension spring is controlled by the arrangement of screw-threaded rod 19 in the roller carrier 9. A tool 63 may be inserted through aperture 2b to move spanner nut 11 to the desired position to fix the proper tension on spring 21. It will be noted that roller carrier 9 carries a vertically extending bearing pin 13 therein on which there is journaled the latching roller 14. The projecting screw-threaded rod member 19 which is mounted in roller carrier 9, as at 9a, as indicated more clearly in Figs. 9 and 10, provides means for adjusting the tension on spring 21. The bearing pin 13 is journaled in opposite bearings shown at 9b in roller carrier 9. A recess 9c is provided in roller carrier 9 for receiving the end of the pin 1a in the eccentric 7. The aperture 9d in the roller carrier 9 permits a tool to be inserted there-

through for adjusting the spanner nut 11, thereby controlling the tension on spring 21 and determining the force with which roller 14 engages the face 8b of the insert 8. The eccentric 7 is maintained in position by pin members 18 which engage a groove in its periphery. The eccentrics each have a central socket 7b therein for receiving socket wrench or key 50 by which the eccentric may be angularly displaced for retracting the roller member 14 and unlatching the door from its normally radially disposed position. In order to prevent ejection of the roller carrier 9 under force of spring 21 when the door is moved out of radial position, we provide a retaining pin 25 projecting through one wall of the housing 2 into the path of the movable carrier 9.

Since roller 14 is forced outwardly by pressure of spring 21, it will resist any ordinary and reasonable effort to move insert 8. However, by exerting a predetermined pressure on hangers 15 and 16, insert 8, through roller 14 and the bearing pin 13, such pressure will cause roller carrier 9 to compress spring 21 and the inward movement of roller 14 releases insert 8, allowing hangers 15 and 16 to swing about the center of the recess 1d shown in Fig. 1.

When it is desired to release the pressure on spring 21, so as to permit the wings to collapse freely, the eccentric 7 may be operated to draw the roller carrier 9 into housing 2. On one side of eccentric 7, there is a projecting lug 7a which enters into the slot 9c in carrier 9. By inserting key 50 in the hexagonal hole and turning eccentric 7 one quarter turn, carrier 9 is drawn back, thus bringing roller 8 flush with the extremity of housing 2, which leaves insert 8, carried by hanger on the door wing, free to swing to one side.

In carrier 1, there are provided four openings 1d and in which openings, the bosses 3d on swinging members 3 fit. Swinging members 3 are free to swing with the center of the bosses as axes. It will be noted that swinging member 3 is held to hanger 15 by pin 6 which is, in turn, anchored to hanger 15 by a set screw 22 which prevents rotation of pin 6. Swinging member 3 has an opening 3b for balls 23 spaced by rod 4. The functions of rod 4 and balls 23 are that when wings are in the position, as shown in Fig. 12, one ball 23 rests in a socket 6a in pin 6 and as long as the center lines of swinging member 3 and hangers 15 and 16 coincide, spacers 4 and balls 23 remain in the position, as shown in Fig. 12, and will remain in this position until the wing is moved to the point where swinging member 3 is stopped by abutment with a portion of carrier 1, as shown in Fig. 13, and when this point is reached, ball 23 will be in a position to enter socket 1e in carrier 1. In this position, the hangers 15 and 16 will cause pin 6 to rotate with it and this action will cause the socket 6a in pin 6 to eject and force ball 23 against rod 4 which will force ball 23 into the socket 1e in housing 1. This action causes swinging member 3 to be held stationary in relation to carrier 1 as long as the center lines of swinging member 3 and hangers 15 and 16 disagree. It will be noted that, attached to hangers 15 and 16 is part 12 secured in position by screws 20, shown in Fig. 15, which acts as an axle for hangers 15 and 16 when center lines of swinging member 3 and hangers 15 and 16 coincide, but when swinging member 3 assumes a position as shown in Fig. 13, part 12 is free to pass through the channel in carrier 1. The purpose of rod 4 and balls 23 is to hold swinging member 3 in the position shown in Fig. 13

until part 12 is in a position so that it may act as an axle.

Figs. 12 and 13 show part 5 whose function is to make a tight joint at the junction of the swinging member 3 with the hangers 15 and 16 in position on the door wings and act in the capacity of a wearing member. Carrier 1 and housing 2 are held together by bolts 24. While we have shown a roller for effecting the latching of the doors, some other form of latching device may be readily employed.

The panic release revolving door hardware of our invention wholly depends upon the roller latching device for maintaining the doors in radial position and is wholly braceless so far as any horizontally extending struts are concerned. We have found the structure of panic release hardware, as set forth herein, highly practical in manufacture, production, assembly and operation, and, while we have described the preferred form of our invention, we desire that it be understood that modifications may be made by those skilled in the art and we intend no limitations upon our invention other than are imposed by the scope of the appended claims.

What we claim as new and desire to secure by Letters Patent of the United States is as follows:

1. In a revolving door structure, a vertical shaft member, a pair of carriers mounted on said shaft member, each of said carriers having diametrically opposed sockets therein, swinging members, each having a stud projecting into a socket in said carriers, door hangers supported by said swinging members and latching means on the ends of said door hangers engaging cooperative latching means on said carriers when said swinging members are in alignment with said door hangers in radial position.

2. In a revolving door structure, a set of door mountings, a vertically disposed rotatable shaft, a pair of carriers mounted on said shaft, said carriers each having diametrically disposed vertically aligned sockets therein, swinging members, each having a downwardly depending stud engaging a socket in said carriers, said door mountings supported by said swinging members, roller members supported by said carriers and means mounted on each of said door mountings for engaging said roller members when said swinging members are aligned with said door mountings in radial position.

3. In a revolving door structure, a set of door mountings, a vertically disposed rotatable shaft, a pair of carriers mounted on said shaft, said carriers each having diametrically disposed vertically aligned sockets therein, swinging members, each having a downwardly depending stud engaging a socket in said carriers, said door mountings supported by said swinging members, roller members supported by said carriers, means mounted on each of said door mountings for engaging said roller members when said swinging members are aligned with said door mountings in radial position, and spring means for urging said roller members into engagement with the aforesaid means.

4. In a revolving door structure, a set of door mountings, a vertically disposed rotatable shaft, a pair of carriers mounted on said shaft, said carriers each having diametrically disposed vertically aligned sockets therein, swinging members, each having a downwardly depending stud engaging a socket in said carriers, said door mountings supported by said swinging members, roller members supported by said carriers, means

mounted on each of said door mountings for engaging said roller members when said swinging members are aligned with said door mountings in radial position, and adjustable tension means 5 for urging said roller members into engagement with the aforesaid means.

5. In a revolving door structure, a set of door mountings, a vertically disposed rotatable shaft, a pair of carriers mounted on said shaft, said carriers each having diametrically disposed vertically aligned sockets therein, swinging members, each having a downwardly depending stud engaging a socket in said carriers, said door mountings supported by said swinging members, roller members supported by said carriers, means mounted on each of said door mountings for engaging said roller members when said swinging members are aligned with said door mountings in radial position, and adjustable tension 10 means disposed in radial positions in each of said carriers, corresponding in number to the number of roller members, and operating to continuously urge said roller members into engagement with the aforesaid means.

25. 6. In a revolving door structure, a set of door mountings, a vertically disposed rotatable shaft, a pair of carriers mounted on said shaft, said carriers each having vertically disposed and aligned sockets therein, swinging members each having a downwardly depending stud engaging a socket in one of said carriers, said swinging members supporting said door mountings, roller members supported by said carriers, engaging means mounted on each of said door mountings for engaging 30 said roller members when said swinging members are aligned with said door mountings in radial position, spring means for continuously urging said roller members into engagement with said engaging means, adjustable devices mounted in 35 said carriers and angularly shiftable to individually retract said roller members with respect to the first said engaging means, and separate interlocking means disposed in each of said swinging members for selectively interlocking each 40 swinging member with the door mounting or the carrier associated therewith.

7. In a revolving door structure, a set of door mountings, a vertically disposed rotatable shaft, a pair of carriers mounted on said shaft, said carriers each having vertically disposed and aligned sockets therein, swinging members each having a downwardly depending stud engaging a socket in one of said carriers, said swinging members supporting said door mountings, roller members supported by said carriers, engaging means mounted on each of said door mountings for engaging 50 said roller members when said swinging members are aligned with said door mountings in radial position, spring means for continuously urging said roller members into engagement with said engaging first mentioned means, eccentric members mounted in the side walls of said carriers and having means thereon operative for individually retracting said roller members with respect to 55 said engaging means, and means for interlocking said swinging members and said door mountings in said radial position and said swinging members and said carriers in collapsed position.

8. Mounting means for revolving doors comprising a vertically disposed shaft member, a pair of carriers on said shaft member, a multiplicity of door wings, hangers on each of said door wings, swinging members interconnecting said hangers and said carriers, and means extending through said swinging members for lock-

ing said doors in collapsed position when said doors are moved to a limiting position away from the normal position thereof.

9. Mounting means for revolving doors comprising a vertically disposed shaft member, a pair 5 of carriers on said shaft member, a multiplicity of door wings, hangers on each of said door wings, swinging members interconnecting said hangers and said carriers, roller members for normally latching said door wings in radial position, and locking means extending through said swinging members for locking said door wings in collapsed position when said door wings have been moved out of radial position to a maximum limit position.

10. Means for mounting revolving doors comprising a vertical shaft, a pair of carriers on said shaft, a set of door wings having hangers thereon, swinging members extending between said hangers and said carriers, an insert carried by 20 each of said hangers and having a cam shaped face thereon, spring pressed roller members mounted with respect to said carriers for normally engaging said cam faced inserts for latching said door wings in radial position, and separate means for interlocking said swinging members with said hangers in said radial position of said door wings.

11. Mounting means for revolving doors comprising a vertical shaft, a carrier and housing 30 mounted adjacent each end of said vertical shaft, a multiplicity of door mountings, swinging members pivotally connected with said door mountings and journaled in said carriers, roller members carried by said housing, means on said door 35 mountings engageable by said roller members for latching said door mountings in radial position, and separate means extending through said swinging members for locking said door mountings with respect to said swinging members in 40 said radial position.

12. Mounting means for revolving doors comprising a vertical shaft, a carrier and housing disposed adjacent each end of said shaft, a multiplicity of door wings, door hangers carried by 45 said door wings, a pin member passing vertically through each of said door hangers, a swinging member pivoted on said pin member and journaled in said carrier, an insert carried by said pin member and having a cam shaped face thereon, 50 roller members vertically disposed in diametrically opposite portions of said housing, and means for yieldably urging the said roller members into engagement with said cam faced inserts for normally maintaining said door wings in radial positions, and separate means extending through 55 said swinging members for locking said door hangers with respect to said swinging members in said radial positions.

13. Mounting means for revolving doors comprising a vertical shaft, a carrier and housing mounted adjacent the opposite ends of said shaft, a multiplicity of door wings, hangers on each of said door wings, swinging members interconnecting said carriers and said hangers, a roller latching device for normally maintaining said door wings in radial positions with respect to said vertical shaft, and means for interlocking said swinging members with said hangers in the normal position of said door wings and interlocking 60 said swinging members with said carriers while permitting removal of said door wings from said carriers when said door wings are in semi-collapsed position.

14. Mounting means for revolving doors com-

- prising a vertical shaft, a carrier and housing mounted adjacent the opposite ends of said shaft, a multiplicity of door wings, hangers on each of said door wings, swinging members interconnecting said carriers and said hangers, a roller latching device for normally maintaining said door wings in radial positions with respect to said vertical shaft, means for interlocking said swinging members with said hangers in the normal position of said door wings and interlocking said swinging members with said carriers while permitting removal of said door wings from said carriers when said door wings are in semi-collapsed position, channel-ways formed in said carriers, and diametrically segmental pivotal locking members carried by said hangers, said diametrically segmental members being adapted to slip endwise of said channel-ways when said door wings are moved to semi-collapsed position to bring said door wings to fully collapsed position.
15. Means for mounting revolving doors comprising a vertical shaft, a carrier and housing mounted adjacent each end of said shaft, a multiplicity of door wings, hangers on said door wings, swinging members interconnecting said hangers with said carriers, spring pressed roller members supported with respect to said housings and operating to normally engage said hangers when said door wings are in radial position, means operative from the exterior of said housings for controlling the latching tension of said roller members with respect to said hangers, and separate means for interlocking said swinging members with said hangers in the radial position of said hangers.
16. Means for mounting revolving doors comprising a vertical shaft, a carrier and housing mounted adjacent each end of said shaft, a multiplicity of door wings, hangers on said door wings, swinging members interconnecting said hangers with said carriers, spring pressed roller members supported with respect to said housings and operating to normally engage said hangers when said door wings are in radial position, separate means in said housing for manually controlling the position of said roller members, a rotatable adjusting screw disposed within said housing and operative from the exterior thereof for adjusting the tension on said roller members, and separate means for interlocking said swinging members with said hangers in the radial position of said hangers.
17. Means for mounting revolving doors comprising a vertical shaft, a carrier and housing located adjacent opposite ends of said shaft, a multiplicity of door hangers, swinging members interconnecting said door hangers with said carriers, a set of four radially disposed passage-ways in said housing, a spring pressed roller carrier mounted for reciprocation in each of said passage-ways, a roller member journaled in each of said roller carriers, means carried by said hangers and normally engaged by said roller members for latching the door hangers in radial position, and separate means for interlocking said swinging members with said hangers in the radial position of said hangers.
18. Means for mounting revolving doors comprising a vertical shaft, a carrier and housing located adjacent opposite ends of said shaft, a multiplicity of door hangers, swinging members interconnecting said door hangers with said car-
- riers, a set of four radially disposed passage-ways in said housing, a spring pressed roller carrier mounted for reciprocation in each of said passage-ways, a roller member journaled in each of said roller carriers, means carried by said hangers and normally engaged by said roller members for latching the door hangers in radial position, means for preventing the ejection of said roller carriers when the door hangers are moved to collapsed position and out of alignment with the passage-ways in said housing, and separate means for interlocking said swinging members with said hangers in the radial position of said hangers. 5
19. Means for mounting revolving doors comprising a vertical shaft, a carrier and housing located adjacent opposite ends of said shaft, a multiplicity of door mountings, swinging members interconnecting said door mountings with said carriers, a set of four radially disposed passage-ways in said housing, a spring pressed roller carrier mounted for reciprocation in each of said passage-ways, a roller member journaled in each of said roller carriers, means carried by said mountings and normally engaged by said roller members for latching the door mountings in radial position, pin members extending across the path of each of said roller carriers for preventing the ejection of said roller carriers when said door mountings are moved to collapsed position out of alignment with said radially disposed passage-ways, and means for interlocking said swinging members with said mountings in the radial position of said mountings, and interlocking said swinging members with said carriers in 35 the collapsed position of said mountings. 15
20. Means for mounting revolving doors comprising a vertical shaft, a carrier and housing located adjacent opposite ends of said shaft, a multiplicity of door wings having hangers thereon, swinging members interconnecting said hangers with said carriers, a set of four radially disposed passage-ways in said housing, a roller carrier mounted for reciprocation in each of said passage-ways, a roller member journaled in each of said roller carriers, means carried by said hangers and normally engaged by said roller members for maintaining the door wings in radial position, and means extending through each of said swinging members for locking said 50 door wings in collapsed position. 40
21. Mounting hardware for revolving doors having panic release and collapsing means comprising a vertically disposed shaft, a pair of carriers on said shaft, a plurality of door wings, 55 hangers on each of said door wings, swinging members interconnecting said hangers and said carriers, latching means disposed between said carriers and said hangers for maintaining said door wings normally in radial position, and locking means for interlocking said hangers and said swinging members in said radial position, said locking means being operative for interlocking said swinging members and said carriers and unlocking said swinging members and said hangers 65 when said door wings have been displaced a predetermined distance from said normal radial position, said hangers thereby being subject to further displacement with respect to said normal radial position. 70

JOHN W. SHIELDS.
THURLOE M. HAGENBOOK.
